COMBINED JUG AND CAP THEREFOR

Albert Jacob, Paris, France (% Colgate-Palmolive Company, 300 Park Ave., New York, N.Y. 10022)

Filed Nov. 2, 1971, Ser. No. 195,063

Claims priority, application France June 1, 1971

Term of patent 14 years

Int. Cl. D9—01

U.S. Cl. D9—40

FIG. 1

FIG. 2

FIG. 3

FIG. 4

FIG. 5

FIG. 1 is a top plan view of a combined jug and cap therefor embodying my new design;

FIG. 2 is a side elevational view, the opposite side being a mirror image of the side shown;

FIG. 3 is an end elevational view;

FIG. 4 is an end elevational view looking from the right of FIG. 2 and showing the end opposite that seen in FIG. 3; and

FIG. 5 is a bottom plan view.

I claim:

The ornamental design for a combined jug and cap therefor, as shown and described.
